UNITED STATES PATENT OFFICE.

JOHN PURLEY TILTON AND WILLIAM SCOTT, OF LEWISTON, MAINE, AS-SIGNORS OF ONE-THIRD TO HERBERT L. PRATT, OF SAME PLACE.

STOP-MOTION FOR LOOMS.

SPECIFICATION forming part of Letters Patent No. 394,893, dated December 18, 1888.

Application filed February 2, 1888. Serial No. 262,779. (No model.)

To all whom it may concern:

Be it known that we, JOHN PURLEY TILTON and WILLIAM SCOTT, citizens of the United States, residing at Lewiston, in the county of Androscoggin and State of Maine, have invented certain new and useful Improvements in Stop-Motions for Looms; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to an attachment to be applied to a loom for weaving cotton cloth or textile goods of any kind, and is designed to prevent imperfections in the woven cloth caused by imperfectly-separated threads or "hitch-backs," so called, which frequently occur in the operation of weaving.

Hitherto in weaving cloth, and especially when weaving high-sleided goods, it not infrequently occurs that the yarns after leaving the warp-beam are crossed or stuck together, and when such yarns reach the lease-rods they press against them, thereby tightening such crossed yarns and often breaking them, thereby producing loose threads and otherwise causing imperfect weaving. If the thread is not broken, it is at least stretched or tightened, thus distorting the figure, and in some cases it is tightened to such an extent as to tear the cloth.

The present invention is designed to obviate these defects by having the lease-rods connected with the belt-shipper by suitable mechanism, as hereinafter described, so that when the crossed thread or threads that are adhering together from any cause press against the lease-rods it causes them to move, this movement being used by suitable connections to operate and throw off the shipper, thus stopping the loom and giving the operator immediate notice of the defect and an opportunity to remedy it.

The drawings accompanying this specification represent, in Figure 1, a plan of part of a loom with the present invention attached. Fig. 2 is a detail view of the device and its

connections with the loom-frame omitted. Fig. 3 is an enlarged detail view of a portion of the device, showing the moving latch and slide-bar. Fig. 4 is a perspective view of the sliding bar. Fig. 5 shows a plan, and Fig. 6 a side elevation, of the latch.

In said drawings the frame of the loom is shown at N, the breast-beam at F, the lay at E, harnesses at D, and warp-beam at A, these various parts being like those ordinarily now in use on looms of this class. At c c are shown two lease-rods of ordinary construction, which extend the whole width of the warp and which divide and separate the adjacent warp-threads. The ends of these lease-rods are fastened into leather straps a a, these latter being slotted to permit the reception of the rods k k', one of which rods, k', forms an arm of the lever M. These slots or loops in the leather straps a a are made in such a manner and of such a size as to snugly fit the rods k k' when they are passed through them. The rods k k' are firmly fastened to the shaft L, this latter being loosely journaled to the loom-frame, so that any movement of the rods k k' simultaneously moves the shaft L. The rod k' constitutes one arm of the lever M, above alluded to, the arm m constituting the other arm. On said arm m is an adjustable weight, t, of sufficient size to keep the lease-rods, lever M, and its connecting mechanism in their proper position during the operation of the loom. The upper end of the rod k' is connected with a long horizontal rod, J, the other end of said rod being securely fastened to a sliding bar, I, said sliding bar resting in ways d, (shown by dotted lines in Fig. 3,) by means of which construction the sliding bar, whenever operated by the rod J, can readily move back and forth.

At G (see Fig. 2) is shown a "filling-stop-motion lever," so called, such as ordinarily used on looms. This lever G, when the loom is in motion, is continuously kept moving by the operation of the cam g, the ordinary function of this lever being to throw off the shipper v when the filling has run out, thereby stopping the loom. This is done by means of fingers coming in contact with the filling, and when the filling is run out they permit the lever G by suitable connections to operate and

throw off the shipper *v*; but as it is no part of this invention it is not necessary to describe it in detail. In the present device this filling-stop-motion lever is made to perform another 5 function in a manner to be now described.

To the arm *f* of the lever *G* there is attached a support or arm, (shown at *i*.) to the upper end of which is loosely fastened a latch, *n*, the said latch being shown in detail in Fig. 5. 10 It will be observed that the support *i* and latch *n* are so fastened to the side of the arm *f* of the filling-stop-motion lever as to project out the width of the support *i* and in no way interfere with the proper operation of the stop-motion lever when operating in its ordinary 15 way.

The sliding bar *I* is constructed, as shown in Fig. 4, with two projections, *e e*, the purpose of these being to prevent the sliding bar from 20 ever getting from under the lever *H*, which latter operates the shipper. One end of this sliding bar is provided with a projection, in which is formed a slot, *o*, in which slot the moving latch *n* rests. The rod *J* is attached 25 to the sliding bar at *p*.

The operation of this attachment is as follows: Assuming the warp, which is shown by dotted lines *r r*, to be in position and the loom in the process of weaving cloth, if there are no 30 cross-threads and no threads sticking together the attachment will be in its normal position, as shown in Fig. 2; but supposing a thread which is coming from the warp-beam and has passed over the whip-roll *B* is stuck 35 to another thread, one of which should properly pass above and one below the lease-rods, in this case when it reaches the lease-rod *c* it presses against it, and if it does not properly separate this moves the rods *k k'*, which in 40 turn and at the same time move the rod *J*. This latter moves the sliding bar *I*, in which rests the latch *n*, sufficiently to allow said latch *n* to drop by reason of its curved surface, and by this dropping the notch (shown 45 at *v*) engages with the lever *H*, and as this lever *G* and latch *n* are always moved by the cam *y* the lever *H* is moved, the said lever being in

contact with the shipper *v*, thus throwing it out of its position, and thereby stopping the loom. In weaving different styles and kinds of goods 50 there are sometimes employed a number of lease-rods, and it is obvious, if the threads are caught while passing each other between the lease-rods, that this gives the attachment the same operation. It makes no difference in 55 what part of the warp the threads are stuck, as by the within-described construction of the rods *k k'* and shaft *L* the motion will have the same effect if the threads should be stuck or crossed at either selvage as well as if they 60 were stuck in any intermediate part of the warp.

Our invention of course extends to the substantial equivalents of the devices shown and described, as well as to said devices themselves. 65

We claim—

1. The lease-rods and straps connecting them, in combination with rods *k k'*, extending up through said straps, the shaft *L*, to which these rods are attached, the weighted 70 arm *m*, extending from said shaft, the rod *J*, extending from the rod *k'*, the sliding bar *I*, connected with rod *J*, the lever *H*, which operates the shipper *v*, the latch *n*, allowed to drop into engagement with lever *H* when the 75 bar *I* is moved, and the cam and lever which operate said latch and lever *H*, substantially as set forth.

2. The cam *g*, lever *G*, lever *H*, and shipper *v*, in combination with the latch *n*, attached to 80 said lever *G*, the sliding bar which allows said latch to fall for engaging lever *H*, the lease-rods, and connections between said lease-rods and said sliding bar, for the purpose set forth.

In testimony whereof we affix our signatures 85 in presence of witnesses.

JOHN PURLEY TILTON.
WILLIAM SCOTT.
